UNITED STATES PATENT OFFICE.

LEVI MCENTYRE, OF CAYUGA, INDIANA.

CAR-REPLACER.

1,142,340.

Specification of Letters Patent.

Patented June 8, 1915.

Application filed August 19, 1914. Serial No. 857,555.

To all whom it may concern:

Be it known that I, Levi McEntyre, citizen of the United States, residing at Cayuga, in the county of Vermilion and State of Indiana, have invented certain new and useful Improvements in Car-Replacers, of which the following is a specification.

My invention relates to new and useful improvements in car replacers or rerailers, 10 and as its principal object aims to provide a rerailing apparatus consisting in a pair of replacers which are positioned on opposite sides of the rails and are adapted to deflect car wheels from an abnormal path back onto 15 the rails.

A further and more specific object of my invention is to equip the replacers each with a novel form of cam holding lever which is so constructed that it may be reversed end 20 for end for properly locking the replacers against movement on the rails, regardless of the direction in which the car wheels are moving.

An additional object of my invention is to 25 construct the replacers and holding devices with such regard to proportion, number and arrangement of parts that they may be cheaply manufactured, will be durable and efficient in service, and are adapted for 30 speedy and convenient application to or removal from the rails with a minimum expenditure of time and labor.

With reference to the drawings, wherein there has been illustrated the preferred embodiment of this invention as it is reduced to practice, and throughout the several views of which similar reference characters designate corresponding parts; Figure 1 is a perspective view illustrating a pair of replacers 40 in operative assembled relation to a pair of track rails; Fig. 2 is a top plan view; Fig. 3 is a transverse section taken on the line 3—3 of Fig. 2; Fig. 4 is an elevation of the rear face of one of the replacers, illustrating in 45 detail the anchor hooks which are employed in securing the blocks to the ties or sleepers; and Fig. 5 is an enlarged perspective view, illustrating a pair of rerailers in disassembled position with respect to the rails.

50 In the embodiment of my invention illustrated in the accompanying drawings, the rerailer apparatus consists essentially in a pair of replacers A and B, which are shown in Figs. 1 and 2 in operative position at the outer and inner sides of the rails C and D,

respectively. The purposes for which the replacers are placed on opposite sides of the rails will hereinafter become apparent as the description of the structural details of the two individual replacers progresses.

60 The replacer A is formed as a solid metallic casting the body portion of which is shaped to produce a pair of parallel vertically disposed side walls 10 and 11, a bridge wall 12 which connects the side walls, and a hook portion, which extends laterally from the junction of the bridge wall 12 and side wall 11 and is adapted to embrace the tread portion or head 14 of the rail A, in the manner best shown in Fig. 3.

70 In order to impart the necessary strength to the body portion of the replacer, I have provided a plurality of spaced, transversely extending webs or connecting walls 15, which are terminally united with the side 75 walls 10 and 11.

75 It will be observed from the foregoing description and upon reference to Fig. 5 particularly, that, while the body portion of the replacer is of hollow construction and is, 80 consequently, light, so that it may be easily transported, it is, at the same time, so designed as to be possessed of all strength necessary for the withstanding of the strains and stresses to which the replacer is subjected upon the passing of rolling stock.

85 In order that the inner side wall 11 of the body portion of the replacer may be properly seated upon the base of the rail, its lower edge is spaced above the transverse 90 terminal edges of the connecting walls 15, as shown in Fig. 3 particularly. A plurality of longitudinally spaced lugs 16 are formed on the lower edge of the wall 11 and are adapted to seat upon the rail base for 95 the purpose of spacing the lower edge of the wall 11 above the spikes 17 employed in securing the rails to the ties.

95 As a means for effecting the secure fastening of the replacers to and the ties, I have 10 provided the transverse terminal edges of the body portion of the replacer with pairs of depending studs or spurs 18, which are sharpened and are adapted to be driven into the ties when the replacer is positioned 105 thereon. In connection with the spurs 18, I have provided for the replacer an anchor hook 19, which is pivoted on a pin 20 at the approximate longitudinal center of the wall 10 and adjacent the lower edge thereof, in 110

the manner best shown in Fig. 4. This anchor hook 19 is provided with two bills 21 and 22, which adapt the hook for engagement with either side of a tie, as will be readily understood. When one of the bill members has been properly engaged with the vertical face of one of the ties, the adjacent button 23 is allowed to swing downwardly into normal position, in which its terminal engages the inactive bill of the hook. It is to be observed that I have provided two buttons 23, which are longitudinally spaced. The purpose in duplicating the buttons is to provide for the anchor hook a holding device when it (the hook) is in either of its two positions. When it is desired to maintain the hook 19 in inoperative position during the application or removal of the replacer, the spring hook 24 is brought into use. This member 24 is in the nature of a helical spring secured, as by a pin or stud 25, to the body portion of the replacer and terminally bent to produce a hook 26. This hook 26 may be engaged with a pin 27 carried by the member 19, as shown in Fig. 4.

It has been found in practice that the spurs 18 and anchoring hook 19 are not sufficient to properly hold the replacer against movement on the rail. For this reason I have provided the cam lever 28, which is engageable against the inner face of the rail C. This lever 28 is formed from a metal bar, the terminals of which are rounded, as at 29, to produce cam heads and apertured, as at 30. The member 28 is properly secured to the block by being inserted through a slot 31 which is formed in the vertical wall 32 which latter member is integral with and depends from the wall 13, the walls 13 and 32 providing the hook portion previously referred to and to be hereinafter more fully described. From the wall 32 and at points immediately above and below the slot 31 extend a pair of apertured ears 34 and 35, through which a pivot pin 36 is projected. This pin 36 passes through the aperture 30, which is located at the inner end of the lever 28, and serves to properly retain the lever 28 in operative position. A small chain 37 is employed in securing the pin 36 to the member 32.

It is now to be observed that each terminal of the lever 28 is provided with a cam head and that, as a consequence, the lever may be reversed end for end, so as to securely lock the replacer against longitudinal shifting on the rail against the impact of rolling stock moving in either direction along the track.

Before taking up the detailed description of the construction of the wall 12 and hook portion of the replacer A, I deem it best to describe briefly the general construction of the replacer B and its fastening

means. The block B is, except as regards the details of construction of its guiding walls and hook portion, substantially similar to the replacer A, including as it does a body portion having the parallel side walls 38 and 39 connected by a longitudinally and transversely curved bridge wall 40. The hook portion 41 is formed integrally with the body portion of the replacer at the junction of the bridge wall 40 and side wall 39 and is adapted to embrace the tread of the rail in the same manner as does the hook portion of the replacer A. Spacing lugs, indicated at 42, are provided for the side wall 39 for the same purpose heretofore ascribed to the lugs 16. Terminal spurs 43, similar to the members 18 both in formation and function, are provided for the member 40. As shown in Fig. 4, the vertical wall 38 of the replacer B is provided with a pair of buttons 44, an anchoring hook 45, and a spring hook 46, all of which are similar in function and in construction to the members 19, 23 and 24 heretofore described in connection with the replacer A. As in the replacer A, there depends from the lateral wall 41 of the replacer B a side wall or plate 47 which is slotted longitudinally, as at 48, to receive the cam headed terminal of the locking lever 49. Vertically spaced, apertured ears 50 are formed immediately above and below the slot 48, to receive the pin 51 by which the lever 49 is held in position. The lever 49 is provided with only one cam head, differing in this respect from the lever 28 of the replacer A.

From the foregoing description, the general construction of the two replacers A and B, and the detailed construction of the locking devices employed in holding the replacers against longitudinal movement on the rails will be readily appreciated, and I will now, therefore, take up the description of the wheel guiding walls and hook portions of the two replacers.

The bridge wall 12 of the block A is longitudinally curved, and is universally inclined throughout its length downwardly in the direction of the rail C. The upper surface of the member 12 is stepped to produce a wheel tread receiving path or surface 52 and a wheel flange receiving surface 53. The vertical walls 54 and 55 which define the two paths or surfaces 52 and 53 are substantially V-shaped, as will be seen upon reference to either Figs. 1 or 2. The apex 56 of the wall 55 extends across the upper surface 53 of the wall 13 to a point in vertical alignment with the inner edge of the rail chair, as will be seen upon reference to Fig. 2. The wall 54 is uniformly spaced throughout its length from the wall 55, and it will, therefore, be apparent that, when a derailed wheel engages the terminals of the wall 12, its flange will engage against the

wall 55, while its outer face will bear against the wall 54. Thus the replacer is provided with guide walls which engage the wheel at two points thereof, and tend, as long as the wheel is in engagement with them, to direct it (the wheel) back onto the rail.

For the purpose, of preventing a wheel from passing completely across the rail into derailed position the wall 13 is provided adjacent its outer edge with a wheel flange receiving channel or groove 57 which is of a depth equal to the width of a wheel flange and is bounded by a longitudinally extending stop wall 58. This wall 58 is in reality a continuation of the wall 32. As will be obvious upon reference to Fig. 2 particularly, the flange of the wheel will, upon riding upon the hook portion, drop into the groove 20 or channel 57 and strike the stop wall 58. The wall 58 being of considerable height will prevent continued lateral movement of the wheel and will cause the flange thereof to resume parallel relation to the inner edge 25 of the rail. The lateral wall of the hook portion is longitudinally curved, its central portion being relatively thick and its terminals being materially reduced. As a result the wheel flange upon moving away 30 from the center of the said lateral wall will drop down to such position that the tread of the wheel will run onto the tread of the rail when the wheel leaves the replacer.

In order to prevent the wheel from sliding too suddenly onto the rail and into engagement with the stop wall 58, I have provided at the terminals of the hook portion the substantially triangular tongues 59 and 60. The inner edges of the tongues extend 40 in parallel relation to the stop wall 58, while their outer edges extend in approximate parallel relation to the adjacent portion of the wall 55. Grooves 59' and 60' lie between the members 59 and 60 and wall 55. 45 These grooves receive the wheel flange and serve to assist the walls 54 and 55 in deflecting the wheel.

The frog and saddle of the replacer B are somewhat similar in construction to the corresponding elements of the replacer A. The wall 40 is longitudinally curved and inclines throughout its length in the direction of the rail. The upper surface of the member 40 is provided with but a single step, differing 50 in this respect from the wall 12 of the replacer A. A substantially V-shaped vertical wall 61 defines, in connection with the upper edge of the side wall 39, a wheel receiving surface or path 62. Inasmuch as the replacer B is placed on the inner side of the rail D, it is obvious that the flange of the wheel will be the only portion of the wheel to engage with the replacer. It will also be apparent that it is only necessary to direct 55 the flange of the wheel back into engage-

ment with the inner or adjacent edge of the rail C instead of causing it to move completely across the rail, as explained in connection with the operation of the replacer A. This operation will be accomplished by the wall 61, for the apex 63 of this wall is located a distance interiorly of the rail D equal to the width of a wheel flange, as will be seen upon reference to Fig. 2 particularly. The inner edge of the wall 40 and adjacent edge of the wall 41 are provided with a common longitudinally extending groove 64, which receives the flange of the wheel during the movement of the same across the body portion of the replacer, permitting the tread surface of the wheel to engage upon and ride along the curved surface of the wall 41. A stop wall, indicated at 65, is engageable by the outer face of the wheel and serves to prevent the same from moving across the rail.

Having thus described my invention, what I claim as new is:—

1. A replacer of the character described including a body portion carrying a hook member, and a cam lever pivoted in the hook member and movable into engagement with the body of a rail, said lever being adapted to be reversed as regards the relation of its cam portion to the web of the rail, whereby impact of a wheel moving in either direction upon the rail will tend to move the rail into more severe engagement with the rail web.

2. A replacer of the character described including a body portion having a hook member integrally formed thereon, a reversible cam lever pivoted in the hook member, the lever being adapted to engage a rail web, an anchor pivoted in the body portion and adapted for movement to engage a rail supporting sleeper, and a ratchet button pivoted to the body portion and engageable with the anchor for holding the anchor in operative position.

3. A replacer of the character described including a body portion carrying a hook member, and a cam lever carried by the hook member and adapted to engage a rail, the said lever being adapted to be reversed end for end.

4. A replacer of the character described including a body portion provided with a bridge wall having spaced vertical walls formed thereon, a hook member including a lateral wall and a vertical wall, a cam lever reversible end for end in the hook member, an upstanding stop shoulder formed on the inner edge of the lateral wall of the hook member, and spaced upstanding tongues formed on the said lateral wall at its junction with the body portion, the innermost of said first mentioned vertical walls inclining in opposite directions away from the said tongues from a point substantially

midway between the tongues, there being grooves provided between the said tongues and the said innermost vertical wall, said hook member being adapted to engage a rail with the lateral wall thereof arranged laterally of the inner edge of the rail with the said cam lever disposed for engagement with the web of the rail and with the said

first mentioned vertical walls inclining toward the rail.

In testimony whereof I affix my signature in presence of two witnesses.
